UNITED STATES PATENT OFFICE.

CARL ENGEL, OF SEATTLE, WASHINGTON, ASSIGNOR OF ONE-HALF TO ERIC JOHNSON,
OF SEATTLE, WASHINGTON.

INTERNAL-COMBUSTION ENGINE.

1,302,143.

Specification of Letters Patent. Patented Apr. 29, 1919.

Application filed May 14, 1917. Serial No. 168,363.

To all whom it may concern:

Be it known that I, CARL ENGEL, a citizen of the United States, residing at Seattle, in the county of King and State of Washington, have invented certain new and useful Improvements in Internal-Combustion Engines, of which the following is a specification.

This invention relates to internal combustion engines, and particularly to what are known as two-cycle engines, although it may be applied to any engine wherein it will be serviceable.

The object of the invention is the perfecting of engines of this type.

The invention consists, principally, first in the provision of improved means for supplying the fuel oil to the engine cylinders; second, to means for interrupting the operation of the fuel-feeding devices to enable the engine to be reversed; third, in pneumatic means to effect starting and reversal of the engine; and fourth, in devices for stopping the supply of fuel to the cylinders when the engine is "racing" or running at an abnormally high speed.

The invention further consists in the novel construction, adaptation and combination of parts, as will be hereinafter described and claimed.

In the accompanying drawings, Figure 1 is a transverse vertical section of an internal combustion engine of the two-cycle type to illustrate the application of the present invention. Fig. 2 is a detail sectional view to an enlarged scale of the fuel-oil injector shown applied in Fig. 1. Fig. 3 is a view partly in side elevation and partly in section of the fuel-oil supply devices and the 40 governor-controlled shut-off mechanism therefor. Fig. 4 is a fragmentary plan view of certain parts shown in Fig. 3. Fig. 5 is a sectional view taken substantially through 5-5 of Fig. 3. Fig. 6 is a fragmentary plan view of Fig. 5. Fig. 7 is a transverse vertical section taken through 7-7 of Fig. 3 and including parts of the reversing apparatus which, for clearness, were omitted from Fig. 3. Fig. 8 is a longitudinal vertical diagrammatic view illustrating a three-cylinder engine with my improved reversing apparatus applied thereto. Fig. 9 is a diagrammatic end view of elements shown in Fig. 8.

55 Referring now to Fig. 1, the numeral 12

designates an engine cylinder which is bored to afford an explosion chamber 13 in which is a piston 14 operatively connected to the crank-pin 15 of a crank-shaft 16 by means of a connecting rod 17. Said cylinder is secured to or formed integral with a crank-casing 18 containing the compression chamber 18¹ which is supplied with air from the external atmosphere through ports 19 for which are provided check or non-return 60 valves 19¹, said valves opening to admit air when the pressure within the case is less than that of the atmosphere and closing when the internal pressure is superior.

Supplemental to said valved ports is provided an air-induction pipe 20 communicating with the cylinder bore through a port 20¹ which is located at an elevation to be uncovered by the piston 14 when at or near the upper end of its stroke.

The connection for the transfer of compressed air from the compression chamber 18¹ is obtained through a passage 21 having a port 21¹ located to afford communication into the explosion chamber 13 and above 80 the piston when the latter is at or near the end of its down-stroke. At the diametrically opposite side of the cylinder from the compressed-air inlet port 21 is an exhaust port 22.

Protruding upwardly from the piston 14 is a baffle-wall 14¹ whose office is to deflect the air entering through port 21¹ so that it will be directed upwardly in the explosion chamber to expel the products of combustion through port 22. This port communicates through a passage 22¹ with an exhaust manifold 22² connected with a silencer indicated by 23 which, in turn, communicates with the exhaust stack 24.

In the illustrated embodiment, the fuel oil is injected into the explosion chamber 13 through the cylinder opening 27 and against the baffle-wall 14¹, to thereby be deflected and spread over the hot walls of the cylinder chamber for vaporization. When this occurs, air is supplied under pressure through pipe 21 and enters the explosion chamber to combine with the oil vapor to afford an explosive mixture which, toward 105 the end of a compression stroke of the piston, ignites by contact with the hot walls of the chamber and piston.

To afford heat to ignite the explosive mixtures before such walls are heated, I pro-

vide in the cylinder head 12² a hollow globe 12³ whose internal space communicates with said explosion chamber for admission of explosive gases into said globe to contact with the wall thereof which is preheated by means of burner 30 supplied with kerosene or other rich combustible oil through a pipe 30¹.

The flame from said burner is directed 10 against the outside of the globe 12³ by means of a funnel-shaped conduit 30².

The preferred form of injector for introducing a spray of fuel oil through the cylinder opening 27 is, as shown in Fig. 2, comprised of a tubular body 31 inserted in said opening and having an axial bore 31² and a valve seat 31³ at its inner end.

32 represents a tip piece secured to the inner end of said body and having a cylindrical bore 32¹ which terminates in a relatively small orifice 32². The injector body, furthermore, is provided with an inlet 31⁴ making communication between the bore 31² and an oil supply pipe 35. An air outlet 25 from such bore is obtained through passage 31⁵ and an air cock 36.

Provided within the bore 32¹ of said cap 30 is a cylindrical valve 37 having a face 37¹ adapted to make a tight fit against the aforesaid valve seat 31³, and is provided in its periphery with a helical groove 37². Said valve is connected by a stem 37³ with a foraminated piston 37⁴ operable within the bore 31².

35 38 denotes a spring interposed between said piston and a shoulder 38¹ of the body bore, and tends to yieldingly retain the valve 37 against the seat 31³. When oil is forced under sufficient pressure against the piston 40 37⁴ to overcome the power of spring 38, the valve is opened and oil is caused to flow with considerable velocity through the foraminations of the piston and thence is caused by the valve groove 37² to take a spiral course 45 and be eventually delivered through the orifice 32² as a spray into the explosion chamber.

The aforescribed elements, with the exception of the silencer, are provided for each of the engine units—that is to say, a cylinder and its associated parts.

In carrying out the invention, I provide apparatus whereby the fuel oil is supplied to the explosion chambers of an engine having a plurality of cylinders and also apparatus which is utilized to furnish compressed air to various cylinders for the purpose of employing the air as a power agent to start and reverse the engine.

The above-mentioned oil supply apparatus 60 comprises a plurality of pumps each having a barrel 40 which is connected by a suction pipe 41, Fig. 5, with an oil supply tank, (not shown), and by means of a delivery pipe 35 with the injector of the respective cylinder. For each of said pump barrels is

provided a plunger 42 and check valves, indicated by 43 and 43¹, for the respective pump inlet and delivery ports.

A plunger is yieldingly held at its outermost position by means of a spring 44 interposed between a collar 42¹ of the plunger and a stuffing-box gland 40¹ for the barrel of the respective pump.

45 represent levers fulcrumed by a pin 46 supported by posts 47 provided on a carriage 47¹ which is adjustably movable transversely of the engine upon a bracket 48 provided on the engine frame. The adjustments of said carriage are attained by any suitable means, as, for example, through the medium 80 of a screw 49 rotatable in a boss 50 of the frame by means of a hand-wheel 49¹ to actuate a nut 51 which is operatively connected by means of a bell-crank lever 52 and a link 52¹ with a lug 47² provided on said carriage. 35

The pump plungers extend through guide apertures provided in the posts 47 so as to be engageable by thrust members 53 pivotally connected to arms 54 extending upwardly from hubs 54¹ mounted upon a shaft 90 55; said hubs are also provided with laterally extending arms 54² and constitute, with the arms 54, a series of bell-crank levers, one for each pump. The lever arms 54² are connected by links 56 with arms 57 of floating 95 levers whose other arms 57¹ are each connected by a pin 58 with the rod 59 of an eccentric 59¹ for the respective pump and provided on the engine shaft 16.

The floating levers 57—57¹ for the connections of all of the pumps are fulcrumed upon a stub shaft or pin 60 provided on the arm 61 of a reversing lever 62 which is fulcrumed upon a stud 63 projecting from the engine frame. 100 105

The thrust members 53 are each provided with a depending foot 53¹ (Fig. 5), which tracks upon a ledge 48¹ provided on bracket 48. To render said members inoperable, as when manually operating the pumps through 110 the instrumentality of the levers 45, the several members may be conveniently tilted into inoperable positions, such as indicated by broken line 53^a in Fig. 5, through the medium of fingers 53². 115 120

Included in the invention are devices whereby the aforesaid pumps are rendered inoperable to supply the fuel oil to the engine with a consequent stoppage of the latter when the speed of the engine is accelerated beyond a predetermined amount. For this purpose, I provide a governor rotatably connected with the engine shaft 16 and desirably mounted on the hub 64¹ of a flywheel 64. The governor comprises a plurality of levers each having arms 65 and 65¹ of unequal lengths, (Fig. 3), and fulcrumed to a pin 66 of a spider 66¹ which is slidably mounted on an end of the wheel hub. The longer arm 65 of a lever has at its extremity 125 130 135

a relatively heavy body 65² which is caused by centrifugal force to be thrown outwardly, radially of the shaft, when the speed of the latter is sufficient to afford the requisite inertia to overcome the power of a spring 67, which acts through the medium of said spider to yieldingly retain the respective lever in the position in which it is represented by full lines in Fig. 3, by reason of the lever arm 65¹ being held against a roller 68 supported by an arm 68¹ of the wheel hub.

As shown, a spring 67 is mounted upon a rod 69 between the head 69¹ thereof and the hub arm 68¹, said rod, as shown, extending through an aperture of the latter and being secured to the spider 66¹.

In the extremity of a lever arm 65¹ is provided a notch 65³ whereinto the respective roller 68 is lodged when a lever is brought into the position in which it is indicated by broken lines 65⁴. The spider 66¹ constitutes a part of a collar 66² disposed concentrically of the shaft and having a peripheral groove 66³ for reception of a ring 70.

At its diametrically opposite sides, the ring 70 is provided with studs 70¹ by which it is operatively connected to the branches of a bifurcated arm 71 of a lever which is fulcrumed to a stand 72 (Fig. 5). The other arm 71¹ of this lever is connected by a link 73 with a lever arm 74 depending from a transversely disposed rocker shaft 74¹ journaled in bearings 75. Another arm 74² extending laterally from shaft 74¹ is connected by a link 76 with the arm 77 of a lever which is fulcrumed to a pin 78 fixedly secured to the engine frame. The other arm 77¹ of the last-named lever is provided with an apertured boss 77² (Fig. 6) in which is socketed an end of shaft 55 upon which are mounted the aforesaid bell-crank levers 54—54² for actuating the thrust members 53 of the various pumps.

In operation, the eccentric 59¹ impart vibratory movements through the medium of eccentric rods 59, levers 57—57¹, links 56 and bell-crank levers 54—54² to the thrust members 53, whereby the power- or fluid-ejecting strokes of the pump plungers are effected.

During such strokes, the springs 44 are compressed and in the outward movements of said members the springs assert their power to effect the suction strokes of the plungers. By manipulating the screw 49, the carriage 48 may be moved toward or from the pump barrels with a consequent shifting of the posts 47 which serve as stops for the collars 42¹ to vary the length of the suction strokes of the respective plungers and accordingly regulate the charges of oil delivered to the engine cylinders.

The hand levers 45 are employed to primarily charge, through the pipes 35, the re-

spective injector bodies 31, and during which the cocks 36 are temporarily opened for the escape of air.

The engine is then put in operation, with the employment of compressed air as a temporary power agent. After the engine is thus caused to operate, the suction strokes of the pistons will draw in explosive charges and thereafter the engine will be driven by the explosion of such charges. When this occurs, the thrust members 53 are rendered operable to reciprocate the plungers through the medium of connecting mechanism from the eccentrics 59¹ for causing the oil to be fed thereby to the cylinders.

In Figs. 8 and 9 I show somewhat diagrammatically, an engine having three cylinders 12¹, 12², 12³ which are respectively connected by pipes 28 with upright valve casings 80¹, 80², 80³ which, in turn, are each connected by a port 81 and a communicating pipe such as 81¹ (Fig. 7) with a reservoir 81² of air under a relatively high pressure. Within said casings are valves 82 arranged to be reciprocated by operating mechanism 90 for closing or opening the respective ports 28¹ to regulate the flow of compressed air from said reservoir to the various cylinders to thereby run the engine.

Between the outlet of each pipe 28 and the respective cylinder is a check valve 29 (Fig. 1), and a valve as indicated by 85 in Fig. 7 may be employed to shut off the air delivery from the reservoir 81².

As shown in Fig. 7, a valve 82 is provided with a stem 83 which is yieldingly held by means of a spring 83¹ against a valve lifter 84 having at its lower end a shoe 84¹ which is normally supported upon flat face 86¹ of a block 86 mounted for rocking movements on a shaft 87. The valve lifting block 86 is formed or provided with a depending lug 86² extending into the space between the tappet elements 88 provided on the upper end of the respective eccentric 110 rod 59.

When the engine is operated by power derived from the fuel oil supplied by the aforescribed pumps, the levers 57—57¹, through which motion is imparted from the eccentric rods 59 to operate the pump plungers, will occupy the positions substantially as shown in Figs. 5 and 7. Under such conditions and with the eccentric rods pivotally connected to the respective pins 58, the tappet elements 88 on the upper ends of the rods will not encounter the block lugs 86².

When the levers 57—57¹ are swung through the agency of the levers 62—61 to one side or the other, the eccentric rods are correspondingly swung to present one or the other of each pair of tappet elements into positions to be actuated by the oscillatory movements of the eccentrics to tilt the valve blocks as indicated, for example, by 86^a in 130

Fig. 9, thereby successively raising the valves in proper sequence to admit compressed air to the engine cylinders for effecting the starting of the engine to drive the engine shaft in a selected rotary direction, or for reversing the engine.

When the levers 57—57¹ are swung about the axis of the fulcrum pin 63, the bell-crank levers 54—54² are caused to be swung 10 into positions in which movements derived from the eccentrics will be insufficient to influence the thrust members 53 to actuate the plungers.

After the engine has been started or reversed, the lever 62—61 is manipulated to restore the levers 57—57¹ in their illustrated positions whereat the eccentric rods are brought into inoperative relations with the air-controlling valves and render the eccentrics capable of imparting motion to the thrust members for operating the oil supply pumps.

The construction and operation of the invention will be understood from the foregoing.

What I claim as my invention, is—

1. In an internal combustion engine, the combination with a system of conduits leading to the power cylinders of the engine, and pumps for forcing fuel oil through said conduits, of a reservoir for compressed air, a second system of conduits leading from said reservoir to said cylinders, devices for controlling the flow of air through the second-named conduits, eccentrics mounted on the engine shaft, and adjustable means actuated by said eccentrics whereby either the first or second-named conduits may be used selectively to the exclusion of the others.

2. In combination, an internal combustion engine, means for supplying combustible fuel to the engine, manually adjustable means to regulate the aforesaid means for governing the supply of the fuel devices regulated automatically from the engine shaft whereby the first named means are rendered inoperative when the engine exceeds a pre-

determined speed, pneumatic means rendered operable by the engine for reversing the latter, and manually adjustable means whereby the first-named means are rendered inoperative when said pneumatic means are employed.

3. In an engine, a fuel-oil supply system, a compressed air supply system, conduits for each of said systems leading to the explosion chamber of each of the engine cylinders, valves for the respective conduits, eccentrics on the engine shaft, means operated by said eccentrics for controlling the valves of the air supply system, means operated by the engine shaft for forcing oil through the conduits therefor, and devices including a manually adjustable floating lever whereby the last named means and the air supply system, respectively, are rendered inoperative and operative for the purpose of reversing the engine.

4. In an internal combustion engine, the combination with a power system comprising pipes leading to the engine cylinders, force pumps for feeding combustible oil through said pipes, eccentrics mounted on the engine shaft, eccentric rods therefor, and operative connections between said rods and the pump plungers for actuating the latter, of a supplementary power system comprising a compressed air reservoir, conduits leading therefrom to the engine cylinders, a spring-closing valve for each of said conduits, operative connections between said rods and said valves for opening the same, and means for controlling said rods whereby they may be caused to effect selectively the operation of either the pump plungers or said valves whereby power is applied to operate the engine through the medium of either of the aforesaid power systems.

Signed at Seattle, Wash., this 2nd day of May, 1917.

CARL ENGEL.
